UNITED STATES PATENT OFFICE.

JOHN A. WAHLSTRÖM, OF SALEM, OREGON.

FLOUR-REEL MACHINE.

SPECIFICATION forming part of Letters Patent No. 484,478, dated October 18, 1892.

Application filed October 21, 1891. Serial No. 409,414. (No model.)

To all whom it may concern:

Be it known that I, JOHN A. WAHLSTROM, a citizen of the United States of America, residing at the city of Salem, Marion county, 5 State of Oregon, have invented certain new and useful Improvements in Flour-Reel Machines, of which the following is a specification, reference being had therein to the accompanying drawings.

10 My invention relates to improvements in flour reels in which a conical air cylinder or channel is placed and fastened into the ordinary revolving flour-reel in conjunction with a peculiarly-constructed reel; and the objects 15 of my improvements are, first, to make a better article of flour, and, second, to carry off by my machine most of the impurities in the stock or feed, whether being in a coarse or light condition, without beating these impurities or tailings into the good stock or flour. I 20 attain these objects by the mechanism illustrated in the accompanying drawings, in which—

Figure 1 is a longitudinal section of the 25 whole machine. Fig. 2 is an end view of the feeding end. Fig. 3 is an end view of the further end of the machine. Fig. 4 is a sectional view of the feeding end. Fig. 5 is an end view of the same, with the head H and feeder D 30 removed the better to show the fan-blades, &c. Fig. 6 is a section of the other end of the reel R, cylinder C, and air-chamber A. Fig. 7 is a view of head L, looking from the inside, with one of the buckets removed to show 35 opening F.

Similar letters refer to similar parts throughout the several views.

At the further end (meaning that end of the machine which is opposite the stock or 40 feed-receiver) is an air-chamber A, which is stationary, connected with the frame of the machine. Into this chamber A the air enters through an opening B, covered and to be regulated with adjustable slats. From air-chamber 45 A the air enters through spider N into the conical air cylinder or channel C, and, passing through air-openings K of rim-bracket J, mingle and joins with the stock or feed, which enters through feeder D. At this station 50 the fans E, which are secured to the double reel-head H and H', and which create the

suction, will then force by their revolving motion the air and stock into the ordinary portion of the reel R, covered with its sifting-cloth, and this forced air thus being mingled 55 with the stock will then force all the coarse and light impurities or tailings to the further end, where the buckets F lift said tailings through the openings F in reel-head L into the tailing-spout V and pass them off, whereas as the good flour is passing through the sifting-cloth, which is spread over reel R, into the conveyers G, finding its ordinary exit and free of tailings or impurities.

The construction of my reel is as follows: 55 The conical air-cylinder C is fastened by spider N and iron rim-bracket J to shaft S. Onto the spider N the reel-head L is securely fastened, whereas to the iron rim-bracket J the reel-head H H' is secured. The fans E are 70 secured within this reel-head H H', and especially draw the air from air-chamber A through cylinder C and openings K into the reel R. The reel-heads H and L are connected by rods M, made of piping or other suitable 75 material, and by these means the reel R and air-cylinder C are securely connected and held in the proper position and distance from each other while revolving on shaft S. The rings or hubs O, supporting the sifting-cloth, 80 are secured to the rods M by bolts b, as shown, and are flush on outside. On the edges or rims of the reel-heads H and L a circular piece of wood P is secured to nail the sifting-cloth to. This circular piece of wood P is fastened to 85 the reel-heads H and L by a circular iron plate T (being of same width as piece P) by bolts c, running through plate T, wooden piece P, and the faces of reel-heads H and L, respectively. 90

Having thus described the construction of the flour-reel R, with its conical air-cylinder C, the operation is as follows, after the machine is put in motion: The air passing through the opening B into the air-chamber 95 A enters through spider N into the conical air-suction cylinder or chamber C, and after passing through the same by the drawing force created by fans E passes through the openings K in rim-bracket J, and then joining and mingling with the feed or stock which enters through feeder D. The air thus forced 100

into and mingled with the stock revolves with the same in reel R, and making thereby a cleaner separation of the flour from its impurities or tailings, and instead of the same being forced with the good flour through the sifting-cloth the air thus created will carry all the coarse and light impurities to the further end of the reel, where the buckets F' lift said impurities through the openings F in reel-head L into the tailing-spout V, whereas the good flour finds its proper exit through the sifting-cloth into the conveyer G, and as a consequence a purer flour is obtained, as the impurities are being kept from breaking fine and thus from mingling with the good flour.

I am aware that prior to my invention flour-reels have been made with ordinary reels and sifting-cloth, and I therefore do not claim such a combination broadly; but

What I do claim as my invention, and desire to secure by Letters Patent, is—

1. In a rotary bolt, a reel having an internal air-chamber open only at the ends and 25 extending substantially from end to end of the reel, a stock-feeding device, and a fan arranged to cause a current of air to pass through said air-chamber and into the space between the air-cylinder and the cloth of the reel, substantially as described.

2. In a rotary bolt, a reel having an internal air-chamber open only at the ends and extending substantially from end to end of the reel, a stock-feeding device, and a fan attached to the reel and arranged to draw air 35 through the air-cylinder and drive it into the

space between the air-cylinder and the cloth of the reel, substantially as described.

3. In a rotary bolt, a reel R, an air-cylinder C, secured within the same, an air-chamber at 40 one end of said reel, and stock-feeding means at the other, in combination with the fan E, arranged in one end of the reel to draw air from air-chamber A through air-cylinder C and drive it into the space between the air-cylinder and the cloth of the reel, substantially as described.

4. In a rotary bolt, a reel R, having heads L and H, buckets attached to one of said ends for lifting the tailings from reel R, an air-cylinder C, secured in said reel R, an air-chamber at one end of said reel, having means for regulating the amount of air passing through the same, and a stock-feeder at the other end of said reel, in combination with a fan E, arranged to draw air from air-chamber A through the air-cylinder C and into the reel R, substantially as described.

5. In a rotary bolt, a stationary air-chamber A, the reel R, having heads L and H, the 60 conical air-cylinder C, secured to said heads and having spiders N and J, a stock-feeder D, and a fan E for drawing air from air-chamber A through air-cylinder C and into reel R, substantially as described.

In testimony whereof I affix my signature, in presence of two witnesses, this 14th day of October, 1891.

JOHN A. WAHLSTROM.
